Attorney

UNITED STATES PATENT OFFICE

ERICH FABIANKE, OF BERLIN-SCHONEBERG, GERMANY

ELECTRIC ILLUMINATION FOR TENTS

Application filed April 29, 1929. Serial No. 359,131.

The illumination of tents, used frequently by scouts and for other purposes and which have to be put up and removed continuously, is not very practical.

This invention has for its object to solve the illuminating problem in a practical manner. With this object in view an electric battery is inserted in the central post of the tent in a cavity in the head portion 10 of the same under the top sleeve with the carrying stud, said battery being connected in a simple manner with a removable lamp holder so that, when this holder is being removed from the post, the circuit is interrupted and closed again at the reinserting of the holder so that the lamp is lighted.

The tent post is not altered and remains as strong as before, the bending-tortion-and buckling moments being even increased by 20 the telescoped brass sleeve which forms a chamber in which the battery and the lamp connection are accommodated. The holder for the lamp has no projections exceeding the diameter of the tent post, and the aperture through which the lamp has to be inserted can be closed, when the lamp is removed, by rotating the brass sleeve on the tent post.

An embodiment of the invention is illustrated by way of example in the accompanying drawing in which:

Fig. 1 shows in side elevation partly in section the tent post with the battery and incandescent electric lamp.

Fig. 2 shows in front elevation the tent post with lamp holder and reflector.

Fig. 3 is a horizontal section through the tent post at the point where the reflector is mounted.

The tent post 1 is fitted as usual with the top sleeve 3 having an upwardly directed stud 2 on which the canvas has to be attached. Between the top sleeve 3 and the tent post 1 a brass sleeve 4 is inserted which 40 has an aperture 7 and a laterally projecting pin 5 adapted to engage with the bayonet slot 6 of the top sleeve 3. In this brass sleeve 4 an electric battery α (dry cell) is mounted, the electrodes 8 and 10 from the battery being connected to the contacts 9

and 15. When the lamp holder 13 is inserted, a downwardly directed extension 14 of the same grips behind the contact spring 15, the contact of the lamp holder 13 bearing against the contacting spring 9 so that 55 the circuit through the lamp is closed.

On the lamp holder a small reflector 12 for the incandescent electric lamp 11 is fixed. The lamp is inserted through the aperture 7 of the rotatable sleeve 4. 60

I claim:

1. An electric illumination for tents, comprising in combination with the tent post, a brass sleeve rotatably mounted on the upper end of said tent post which has a cavity in 65 its upper portion, said brass sleeve having an aperture, a laterally projecting pin on said brass sleeve, a top sleeve of said tent post having a bayonet slot in its lower edge adapted to engage over said laterally projecting pin, an upwardly projecting stud on the top end of said top sleeve adapted to hold the tent canvas, a dry battery in said cavity of the tent post having two electrodes, a contact spring connected to one electrode arranged behind the aperture in said brass sleeve, a contact spring on the outer surface of said brass sleeve connected to the other electrode of said battery, a lamp holder, a 70 incandescent lamp in said lamp holder, a reflector on said lamp holder, and a downwardly extending contact spring on said reflector said lamp holder with reflector designed to be inserted through said aperture of said brass sleeve so that the circuit 75 through said lamp is automatically closed at the inserting of the lamp holder and automatically interrupted at the removing of said lamp holder.

2. An electric illumination for tents as 80 claimed in claim 1, comprising in combination with the tent post having a cavity for a dry battery and with a rotatable brass sleeve having an aperture for the insertion of an incandescent lamp with holder, said 85 brass sleeve adapted to be rotated on said tent post when said lamp holder has been removed so that said aperture is closed.

In testimony whereof I affix my signature. ERICH FABIANKE. 100
